UNITED STATES PATENT OFFICE.

AUGUSTUS J. PENOTE, OF CLEVELAND, OHIO.

EXCAVATING MACHINE.

Application filed October 10, 1923. Serial No. 667,623.

To all whom it may concern:

Be it known that I, AUGUSTUS J. PENOTE, a resident of the city of Cleveland, in the county of Cuyahoga and State of Ohio, have 5 invented certain new and useful Improvements in Excavating Machines, of which the following is a specification.

This invention refers to improvements in excavating machines, and especially to the 10 type known as traction excavators, or ditching machines.

One of the objects of my invention is to 15 improve the type of excavating machines wherein a rear excavating wheel is employed by mounting the same upon a motor driven frame or truck, so that the entire machine may advance as the wheel rotates thereby progressively digging a trench or 20 ditch and conveying the material removed to one side of the trench. It is a special object of my improvement to accordingly reduce the weight of the machine and the power required for doing the essential work, without reducing the speed of excavation, 25 the convenience of operation, or the efficiency of the mechanism.

I have mounted the machine here disclosed on caterpillars, as the sole supporting means therefor, and by mounting the engine 30 and main shaft longitudinal of the entire frame, I have eliminated and modified certain connecting drive parts and thereby reduced the weight of the entire unit. To do this I have mounted the excavating wheel a 35 little nearer one side of the machine than the other, and placed the engine at the forward end on the opposite side from said wheel, thus balancing the weight of the mechanism both laterally and longitudinally.

It is a particular object of my invention 40 to mount the excavating wheel nearer one side thereof as above explained so that the wheel may operate very close to one of the caterpillar drivers, and yet not require so wide space or clearance beyond said driver as would otherwise be necessary. As a further feature of this improvement I have emphasized therein, a means for mounting said 45 excavating wheel including rearwardly in-

clined posts, so that the raised or stored position of the wheel for purposes of transportation will position the same progressively forward over the tractors as the wheel is raised upon the posts.

With these and other objects in view as 55 will appear as the description proceeds, my invention embodies structural features, as described in the specification, recited in the appended claims, and illustrated in the 60 accompanying drawings in which:

Figure 1 is a view of the improved machine in side elevation in full lines the lowered or working position of the excavating wheel as it appears in operation;

Figure 2 is a similar view, but showing 65 the excavating wheel in the raised or inoperative position for the purpose of transportation, and with many parts in the central portion of the structure broken away 70 to show mechanism otherwise concealed;

Figure 3 is a plan view of the forward portion of the tractor mechanism and driving means therefor, and shown on a greatly 75 enlarged scale;

Figure 4 is a plan view of the rear end of the machine on the same scale as Fig. 3, and

Figure 5 is a detail of the transmission drive mechanism for the tractor belts, in 80 section.

In these views the reference character 1 designates sill members which may be formed of channel-bars which support a 85 super-structure composed of angle-bars 2 which constitute the main frame of the machine. This main frame is carried as a unit upon a base frame comprising cross-bars 3 and longitudinal members 4, the latter extending at each side of the machine and supporting upon their ends bearings 5 in 90 which are mounted stub-shafts 6 extending from sprocket wheels 7 that have driving engagement with the endless traction belts 8. The latter are of the composite form, 95 each belt comprising a pair of endless driving members *a* and *b* which are laterally spaced somewhat but integral, and both mounted upon the same sprocket wheel 7. The forward portion of the main frame 1, 2 projects preferably beyond the described 100

running gear and provides a mounting for an engine 9 which is preferably of the internal combustion type, and furnishes power for driving the described running gear and 5 the excavating wheel 10, and also for raising and lowering the latter when desired.

For reasons explained later, it is to be noted that the engine 9 is mounted appreciably nearer the left-hand side of the frame 10 (see particularly Fig. 3) to counterbalance the effect of the desirable positioning of the wheel 10 somewhat on the righthand side, as shown in Figs. 3 and 4. It will later be shown that the same power may, by suitable 15 control by means of clutches and gears, also serve to steer the machine while being transported. The distribution of power for the purpose specified is effected from the main engine shaft 30 which extends lengthwise of 20 the entire machine and mounted on the left side in alinement with the engine.

The adjustable mounting for the excavating wheel 10 comprises a pair of elongated parallel arms 11 which are rigidly connected together in spaced relation to accommodate between them the upper portion of the excavating wheel, the forward ends of said arms being pivoted as indicated at 12, upon a carriage 13 vertically adjustable 30 upon inclined posts 14 which comprise a rear portion of the main frame 1, 2. Said posts are inclined forwardly at a considerable angle so that an adjustment of the carriage 13 upwardly and forwardly to establish the inactive 35 position of the parts, accomplishes also a forward shifting of the arms 11 and the excavating wheel. This wheel 10, as is the usual practice, has the form of an annulus interiorly journaled upon rollers 15 arranged at the apices of a tri-angular frame 16 which is secured to and depends from the arms 11. The numeral 17 designates the common series of combined cutter and bucket members peripherally carried by the 40 wheel 10. 18 represents a belt conveyor extending transversely through the cutter wheel above the arms 11 and mounted upon the pulleys 19 secured to the arms 11 by rods 20.

50 Mechanism is provided for elevating the excavating wheel 10 relative to the frame and comprises a pair of cables 21 guided over pulleys 24 mounted at the upper extremities of posts 14, the forward ends of 55 each being looped about pulleys 22 secured to the rear ends of the arms, and the ends of the cables anchored as at 23 adjacent the pulleys 24. The free ends of the cables are led to a pair of drums 27 fixed to rotatably-mounted shaft 28 driven from shaft 25 through the intermediacy of worm 31 engaging worm wheel 29 fast to shaft 28. Shaft 25 is, together with its related parts, mounted on the beam 26 supported at the front by a standard 2 and secured at the rear to post

14. Shafts 25 and 30 are parallel and are operatively connected by sprocket chain 32. It is to be understood that parts 21 to 24, as well as 11 and 29, are duplicated to properly balance the sides of the load.

70 Adjacent and parallel to drums 27 is mounted another pair of winding drums 33 adapted to be rotated by shaft 35 on which it is fixed through the agency of worm and gear mechanism 34 and 36, the worm being mounted on shaft 25. From reels 33 extend cables 38 on pulleys 41 mounted on posts 14 in alinement with 24, and thence pass down to pulleys 39 carried by the U members 40 mounted on the inner ends of arms 11 and then pass back to the anchor pieces 23 on the uprights and attached thereto. Clutches 37 and 42 are provided for locking or releasing the worms 31 and 34, respectively, and levers 43 and 44 actuate the clutches, as will be understood. 45 and 46 designate bands for selectively determining a choice of speeds by means of the provision of a planet transmission mechanism whose details are well known, and since it is not claimed in detail in this case, it is not illustrated further. 80 Actuating levers 47 and 48 are provided for said bands.

85 The dredging wheel 10 is driven by means of pinions 57 engaging gears whose teeth 58 are mounted laterally of the rim. Said pinions 57 are driven by shaft 55 which has splined to its ends drive sprockets 56 which are driven by sprocket chains 53 led through the take-ups 54. Shaft 50 is driven from shaft 30 by chain 49 on suitable sprockets, shaft 50 rotating a worm alining therewith which engages a worm wheel driving a differential gear mechanism which includes shaft sections 51 bearing on their ends sprockets 52 for driving chains 53. Thus chain 49 drives wheel 10 by differential gearing affording a well-balanced drive in which both chains 53 will always be taut. The shaft 55 has also mounted thereon a beveled gear 59 which drives cross shaft 62 by engagement with beveled gear 61 mounted on the former by which the conveyor belt 18 is actuated, chain 63 on 62 driving a sprocket on the shaft of the reel 19 for such purpose.

100 The tractor belts 8 are driven from a counter shaft 60 which is driven from main shaft 30 by alternative means; the chain 72 serving to connect the two shafts by direct sprocket drive, the clutch 64 actuated by lever 65 determining the use of this connection; or the chain 71, driving shaft 60 through the intermediacy of a reducing gear comprising beveled gears 74, shaft 75 mounting a worm thereon and engaging with a worm wheel 77 on shaft 60, there being preferably a transmission gear mechanism, designated 73 as a whole, between the sprocket from 71 and the gears 74, which transmission mechanism will be later described.

Connection is usually made by chain 72 when transporting the machine along the highway from place to place, but by chain 71 when in operation in dredging. Clutch 67 and lever 68 serve to connect the chain 71 in driving connection, and clutch 69 and lever 70 connect the gear drive for the dredging wheel, as will be understood. Pulley 66 serves as the usual fly wheel, and lever 76 actuates a clutch connecting shaft 60 to the worm wheel 77.

Shaft 60 drives the belts 8 by worm and gear 81 and 82 which drive cross shafts 84 having sprockets 85 at their ends, each driving a chain 83, as shown in Figs. 1 and 3. These chains drive sprockets 87 on shafts 86 which carry sprockets 7 connected directly to the belts. These drive connections are not rigid and direct, but the tractor belt 20 on each side is driven through a differential gear system of well-known character, whereby tightening brake bands 80, selectively applied to pulleys 93 on shafts 84 at the proper side of the machine, will serve to 25 guide or steer the latter toward the side whose bands are actuated with greatest force. The brake bands are tightened by a rocking cross shaft 92 which is actuated by a handle lever 79, a system of cables 88 connecting the bands on one side to the lever, while the arm 91 on the opposite end of the shaft 92 has connections with the bands on the other. A rocking of the shaft will loosen 30 one set of bands and tighten the other. 78 35 designates actuating levers for the usual slip transmission gear bands for a common type of internal combustion engine. The tractor belts 8 may be tightened in adjustment by separating the bearings 5 by means of rods 40 89 and nuts 90 thereon.

The gear mechanism before referred to by the numeral 73 comprises means to attain three speeds and reverse, and transmits power from the sprocket driven by chain 45 71 to the bevel gears 74, the sprocket driving shaft section 94 and the section 95 driving gears 74. For this purpose, a counter shaft 96 is mounted in the casing and has mounted thereon a larger and narrow gear 50 97 permanently in engagement with a wide gear 98 keyed to shaft section 94, and narrow and wide gears 99 and 100, respectively. Gears 101 and 102 are slidably adjusted on shaft section 95 against rotation, the former 55 adapted to gear with 99 for second speed, and the latter with 100 for low speed. The idler shaft 103 carries a gear 104 in permanent engagement with 100, and another gear 105 at the other end for engagement with 60 102 for reverse drive, as will be evident. For direct or high speed drive, gear 101 has connected on its left face an internal gear or spline which is adapted to enclose gear 98 therein, when shifted in that direction, so 65 that two shaft sections will rotate together.

Details of the bearings or of the particular manner of keying the parts on the shaft sections, or of mounting the latter in accurate alinement, are not shown or described, for no claims are made for them per se.

Operation: In inoperative position, with parts at rest, the various clutches are released and the dredging wheel raised, as shown in the view in Fig. 2 of the drawings. If then, the machine is to be transported 70 under its own power, which will obviously be desirable at a speed much greater than that employed when in dredging operation, clutch 64 is engaged by lever 65 and shaft 60 is driven through chain 72, and thereby 75 the chains 83 actuate the tractor belts 8 to advance the machine at relatively high speed. When dredging, it is clear that the machine as a whole should advance much slower, and to effect this, clutch 67 is thrown 80 into engagement by lever 68 and thereby 85 shaft 60 is driven through the intermediacy of chain 71 and its connected reducing mechanism as before described. It is to be noted, however, that, in addition to a permanently connected reducing mechanism, there is also provided the triple speed gearing 90 93 above described, which is designed to vary the advance of the machine in accordance with the resistance encountered, which latter will vary with the different character 95 of soils to be dredged. In general, the high speed is used where light soil such as sand or gravel is to be excavated, the other two speeds being employed where clay or other harder material is to be removed. The reverse is provided to temporarily withdraw 100 the machine from its advanced position to enable rock or other obstructions to be removed which cannot well be lifted by the 105 excavating wheel.

While being propelled on the highway at high speed or very slowly when dredging, the machine is guided or steered by proper manipulation of the lever 79 which guides the machine to the left when moved upward and backward, as shown in Fig. 1; and to the right when moved forward as in said view. This constitutes a very effective steering means.

Lever 70 actuates clutch 69 to start the drive of the wheel 10 or to release it, and chains 53 driving gear 59 and associated parts, actuate the conveyor belt 18 to remove the material emptied into it from the buckets 17 of the revolving wheel 10.

The lever 43 controls clutch 87 to determine the raising of the extreme ends of the arms 11 on their hinges 12, and lever 44 actuates clutch 42 to control the raising of the hinged ends of the said arms 11 on the supporting posts 14. It will therefore be seen that all parts of the machine are controlled by levers adapted to be operated from the same side thereof, so that it may 125 130

be operated by a single operative, and that a great range of speed is provided for driving the same forward while the excavating wheel is in lowered and dredging operation, 5 and a far greater speed provided for a reasonably rapid transit when the machine is to be propelled over the highways for removal to a distant place for operating there. These changes are provided for without the 10 strain consequent upon shift of power from shafts at angles to the drive or engine shaft, and by the very desirable arrangement of a system of counter shafts all of which are mounted lengthwise of the machine. This, 15 with the further desirable mounting of the engine shaft longitudinal of the machine but lateral of the longitudinal center thereof opposite to the side carrying the greater weight of the dredging wheel, provides an 20 especially effective construction, balanced as to weight both longitudinally and laterally, compact in assembly, and capable of very strong and secure positioning upon the base of the carriage.

25 It is quite evident that a wide choice of alternative operations is, by my improved machine, at the disposal of the operative who, seated at one side of the machine in reach of these various levers, may be called 30 upon to meet conditions in an emergency, such as the event of the dredger striking a rock, or possibly a cross pipe such as a water or gas main, or a stratum of much harder soil than that in which the machine had been 35 operating. In the latter case, he may operate small levers to shift the splined gears 101 and 102 to throw in a slower speed of the tractor belts relative to the rotation of the wheel 10, (such levers are not shown as 40 they are mounted and operate in a conventional manner); or, he may, by moving the proper levers 78, greatly reduce the speed of all rotating parts, or as a last resort, he may disconnect the drive of the wheel 10 and of 45 shaft 60, without stopping the engine or its shaft 30, though this latter expedient need seldom be resorted to. If a solid obstruction be encountered, he may at first lower the speed of drive by actuating the transmission 50 levers reducing the speed of the tractor belts, or he may release the drive for both wheel 10 and said drive belts, though permitting the engine to run. He may then reverse the direction of drive for said belts 8 for a moment after which the wheel may be raised 55 by operating the reels 27 by shifting lever 43. The machine can then be propelled forward until the obstruction, if a fixed one, is passed over, when the wheel may then be lowered again and dredging resumed as at 60 first.

When the excavating wheel is raised, it is shifted somewhat forward over the frame due to the inclination of posts 14 on which 65 they are carried, whereby the wheel serves

to counterbalance the overhanging forward portion of the machine carrying the engine. This longitudinal shifting of the heavy dredging wheel in raising it to stored position considerably reduces the minimum 70 length of the machine as compared with machines heretofore employed for a like purpose.

An especial advantage is to be noted in the use of tractor belts as the sole running 75 gear for supporting my machine, its use making possible the desirable even distribution of the essential load of the machine over the surface upon which it travels, thereby lessening possible damage to the surface, 80 providing very positive tractive force in propulsion, and at the same time making possible very compact assembly of the entire unit.

Attention is also called to the provision 85 of differential gear mechanism for driving the excavating wheel, the advantage of said construction arising from the fact that my dredging wheel has a driving gear on both faces of the rim but no hub or spokes. 90 This renders it essential that the driving force should be applied with substantially equal force to both gears. I have accomplished this by driving a cross shaft 55 by a pair of sprocket chains 53 which are themselves driven from alined shaft sections 51 through a differential mechanism, as above stated. I claim no inventive merit in the differential mechanism per se, but believe it to be patentably novel to use the same in 100 driving a dredging wheel as above explained.

Having set forth the principles of my invention, and described and illustrated an embodiment thereof for practical use, what I 105 claim and desire to secure by Letters Patent, is,—

1. An excavating machine comprising a running gear, a frame mounted thereupon, an excavating wheel and an engine mounted on said frame in parallel planes longitudinal of the latter, the engine extending forwardly and the wheel rearwardly of the said running gear in counter-balancing relation, means for actuating said running gear and wheel including parallel counter shafts and an engine shaft, all longitudinal of the supporting frame, and clutch-controlled driving connections between said shafts and between the latter and the running gear and wheel, respectively.

2. An excavating machine comprising a running gear, a frame mounted thereupon, an excavating wheel and an engine mounted on said frame in parallel planes longitudinal of the latter, the wheel being positioned substantially nearer one side than the other, the engine extending forwardly and the wheel rearwardly of the said running gear in counter-balancing relation, means for 130

actuating said running gear and wheel including parallel counter shafts and an engine shaft, all longitudinal of the supporting frame, and clutch-controlled driving connections between said shafts and between the latter and the running gear and wheel, respectively.

3. An excavating machine comprising a running gear, a frame mounted thereupon, an excavating wheel and an engine mounted on said frame in parallel spaced planes longitudinal of the latter, the engine extending forwardly and the wheel rearwardly of the said running gear in counter-balancing relation, and said engine and wheel positioned, respectively adjacent opposite sides of said frame, means for actuating said running gear and wheel including parallel counter shafts and an engine shaft, all longitudinal of the supporting frame, and clutch-controlled driving connections between said shafts and between the latter and the running gear and wheel, respectively.

25 4. An excavating machine comprising a running gear including spaced tractor belts, a frame mounted thereupon, an excavating wheel and an engine mounted on said frame in parallel planes longitudinal of the latter, the engine extending forwardly and the wheel rearwardly of the said tractor belts in counter-balancing relation, means for actuating said tractor belts and wheel including parallel counter shafts and an engine shaft, all longitudinal of the supporting frame, and clutch-controlled driving connections between said shafts and between the latter and the tractor belts and wheel, respectively.

40 5. An excavating machine comprising a running gear including spaced tractor belts, a frame mounted thereupon, an excavating wheel and an engine mounted on said frame in parallel planes longitudinal of the latter, the engine extending forwardly and the wheel rearwardly of the said tractor belts in counter-balancing relation, means for actuating said tractor belts and wheel, the former at a plurality of speeds, selectively, relative to the wheel, said means including parallel countershafts and an engine shaft, all longitudinal of the supporting frame, and clutch-controlled driving connections between said shafts and between the latter and the tractor belts and wheel, respectively.

55 6. An excavating machine comprising a running gear, a frame mounted thereupon, an excavating wheel and an engine for actuating said running gear and wheel, said wheel and engine being carried in counter-balancing relation beyond opposite ends of the running gear, and in laterally balanced relation at opposite sides of but within the outlines of said frame, respectively.

7. An excavating machine comprising a

running gear, the latter comprising laterally spaced tractor belts, an excavating wheel supported by said running gear beyond one end of said belts, and an engine similarly supported beyond the other end thereof and counter-balancing said wheel, means for driving the wheel and the belts from the engine, said belt driving means including means for slackening the speed of either of said belts without interfering with the propulsion force of the other to thereby steer the machine.

8. An excavating machine comprising a running gear, a frame mounted thereupon, an excavating wheel and an engine for actuating said running gear and wheel and engine being carried in counter-balancing relation beyond opposite ends of the running gear, and in laterally-balanced relation at opposite sides of said frame, respectively, an elongated supporting element for said wheel mounted longitudinally of said frame and pivoted at one end thereto, cables for raising and lowering the respective ends of said elongated element, drums engaged by said cables, driving means for said drums including clutch-controlled connections between said engine and drums, adjustable to alternatively establish a drive to said drums, selectively.

9. An excavating machine comprising a running gear, the latter comprising laterally spaced tractor belts, an excavating wheel supported by said running gear beyond one end of said belts, and an engine similarly supported beyond the other end thereof and counter-balancing said wheel, said engine and wheel being mounted in laterally-balanced relation at opposite sides of said frame, respectively, driving means for driving the wheel and the belts from the engine, the latter including means for slackening the speed of either of said belts without interfering with the propulsion force of the other to thereby steer the machine.

10. An excavating machine comprising a running gear formed of spaced tractor belts constituting the sole support thereof, a frame mounted thereupon, portions thereof projecting forwardly and rearwardly beyond said belts, an excavating wheel, and an engine for actuating said belts and wheel, said wheel and engine being carried in counter-balancing relation on said forward and rearward portions of the frame, respectively.

11. An excavating machine comprising a running gear formed of spaced tractor belts constituting the sole support thereof, a frame mounted thereupon, and projecting forwardly and rearwardly beyond said belts, an excavating wheel, and an engine for actuating said belts and wheel, said wheel and engine being carried in counterbalancing relation on said forward and rearward por-

tions of the frame and in laterally balanced relation at opposite sides of said frame, respectively.

12. An excavating machine comprising a running gear, an excavating wheel having gears on its faces and supported by said running gear, an engine supported on said running gear, and means for driving said wheel gears from the engine comprising a cross shaft, gears on said shaft for engaging the gears on the face of the wheel, and differential gear mechanism for applying rotative power to the ends of said cross shaft.

13. An excavating machine comprising a running gear, an excavating wheel having gears on the faces of its rim and an engine supported by said running gear, and driving means connecting the wheel and engine for driving the former, and comprising gears on the external face of the wheel rim, a cross shaft having gears mounted fixedly thereon for engaging the gears on the wheel rim, sprockets mounted on the respective ends of said cross shaft and keyed thereto,

sprocket chains for independently driving the said sprockets, shaft sections having means for driving said chains, and differential gear mechanism for driving said shaft sections.

14. An excavating machine comprising a running gear, a frame mounted thereupon, an excavating mechanism and an engine mounted on said frame in parallel planes longitudinal of the frame, the engine extending forwardly and the excavating mechanism rearwardly of the said running gear in counter-balancing relation, the said engine and its shaft being longitudinal of said frame but nearer one side thereof than the other, the said mechanism being positioned nearer the opposite side of said frame in laterally-balanced relation with the engine, and driving mechanism connecting said engine shaft with said excavating mechanism.

In testimony whereof I hereunto affix my signature,

AUGUSTUS J. PENOTE.
